UNITED STATES PATENT OFFICE.

HENRY J. GAISMAN, OF NEW YORK, N. Y.

SAFETY RAZOR.

Application filed August 19, 1921. Serial No. 493,532.

To all whom it may concern:

Be it known that I, HENRY J. GAISMAN, a citizen of the United States, and resident of New York city, Borough of Manhattan, in the county of New York and State of New York, have invented certain new and useful Improvements in Safety Razors, of which the following is a specification.

My invention relates to improvement in safety razors and more particularly to the class of razors having a movably supported blade and movable guard provided with means to cooperate with the blade to retain it in shaving position respecting the guard, and to release the blade for removal and replacement as well as for cleaning and stropping.

The object of my invention is to provide simple, cheap and effective means to movably support a guard in a safety razor to retain and release a blade as required, whereby the blade edge may be retained in proper shaving position respecting the guard.

My invention comprises novel details of improvement that will be more fully hereinafter set forth, and then pointed out in the claims.

Reference is to be had to the accompanying drawings forming part hereof, wherein—

Figure 1 is a plan view of a safety razor embodying my invention;

Fig. 2 is a side view of Fig. 1;

Fig. 3 is an underside view in section on line 3, 3, in Fig. 2;

Fig. 4 is an enlarged section on line 4, 4, in Fig. 1;

Fig. 5 is a section on line 5, 5, in Fig. 2. Similar numerals of reference indicate corresponding parts in the several views.

The numeral 1 indicates the main frame of my improved safety razor which may be of any suitable construction, shown provided with a handle 2 which may be attached to the frame in any well known manner. Frame 1 comprises a base portion 1^a and spaced uprights 1^b through which a strop may be passed from side to side. A blade holder 3 is shown movably supported upon frame 1 between uprights 1^b upon a shaft 4 pivoted between said uprights. The blade holder 3 may be of any well known variety adapted to securely retain the blade 5, said blade holder being shown in the form of spaced plate-like members 3^a to receive the

heel of the blade therebetween and with stops 5, 6, at the ends to retain the blade removably in the holder. A guard for the blade edge is indicated at 7 shown provided with guard teeth 8 arranged in any well known manner. Said guard is shown provided with stops or hooks 9 adjacent to its corners to engage the blade edge to retain the blade in shaving relation to the guard teeth. Said guard is pivotally supported upon base 1^a to rock or tilt relatively thereto to move the guard teeth and the stops 9 with respect to the blade edge. I have shown the guard 7 provided with laterally or downwardly extending lugs or ears 10 pivotally connected by pivots or rivets 11 with lugs or ears 12 extending from the ends of base 1^a. Lugs 12 are shown located outside of lugs 11 and in juxtaposition thereto, whereby the guard is rockably retained from lateral or endwise displacement. The guard member 7 is provided with an outward projection or thumb piece 13 shown projecting beyond the rear portion of the razor and provided with an opening 13^a receiving handle 2, said opening being of sufficient size to permit the projection 13 to be moved along the handle when the guard is to be rocked. It will be observed that the pivots 11 are located between the guard teeth 8 and handle 2, hence between the guard teeth and the projection 13. The projection 13 operates below base 1^a so that when said projection is pushed up it will cause the guard to swing away from the blade edge. The movement of projection 13 will be limited by the base 1^a, Fig. 4. To retain the guard in set position its upper surface is curved to engage the correspondingly curved under surface of base 1^a, said curves being described around the axis of pivot 11, (Fig. 4), so that the guard member may rock in frictional engagement with the base to retain the guard set. When making the guard its said curved portion may be bowed slightly upwardly to engage base 1^a under tension when the pivots 11 are set in the lugs, having slight clearance between the end portions of the guard member and base 1^a.

I have illustrated my improvement in connection with means for rocking the blade while in frame 1 comprising a roller 14 journaled in the frame between shaft 4 and base 1^a, said shaft having a gear 15 in mesh with a gear 16 secured to roller 14. A

strop may be passed between roller 14 and base 1^a and when held taut the blade may be rocked by reciprocating the frame along the strop with the under surface of roller 14 in engagement with the strop, in a well known manner.

When the parts are in the position shown in Fig. 2 stops or hooks 9 will engage the blade edge to retain the latter in shaving relation to the guard teeth 8. When it is desired to release the blade from the guard, the projection 13 is pushed toward base 1^a, whereby the guard will be rocked to move its stops 9 away from the blade edge to release the latter, as indicated in full lines in Fig. 4, whereby the blade may be raised from the guard by rotating it for removal and re-placement, for cleaning, and for stropping, since with the blade raised from the guard the strop may be passed between roller 14 and base 1^a, (Fig. 4). When it is desired to replace the blade in operating relation to the guard the blade is lowered to rest against the guard member, (which is then lowered), the projection 13 is drawn down, (as to the dotted position in Fig. 4), causing the outer end of the guard to rise toward the blade edge to engage the stops or hooks 9, whereupon the guard and blade will be in the full line position shown in Fig. 2 and the dotted line position shown in Fig. 4.

My improvements are simple in construction, cheap to manufacture, not liable to get out of order, readily operable, and effective in use to retain the blade for shaving and to release the blade for other purposes before specified.

Changes may be made in the details of construction set forth, within the scope of the appended claims, without departing from the spirit of my invention.

Having now described my invention, what I claim is:—

45. 1. A safety razor comprising a frame, a blade holder movably carried thereby, a handle projecting from the frame and a guard provided with stops for the blade, said guard being pivotally carried by the frame between said stops and said handle to rock to engage and release the blade.

55. 2. A safety razor comprising a frame having a handle, a blade holder movably carried by the frame, a guard having stops to engage the blade, and means pivotally supporting the guard upon the frame between said stops and handle, said guard having an integral projection for the finger extending beyond the pivots of the guard beyond the handle on the side opposite the stops.

60. 3. A safety razor comprising a frame having a handle, a blade holder movably carried by the frame, a guard having stops to

engage the blade, and means pivotally supporting the guard between said stops and handle, said guard having a projection extending beyond the handle, said projection having an opening receiving said handle.

4. A safety razor comprising a frame having a handle and a base extending on one side of the handle, means on the frame to movably support a blade, and a guard pivotally carried by said base on one side of the handle and provided with stops to engage the blade, said frame and guard having slidably engaging surfaces concentric with said pivotal means to frictionally retain the guard.

5. A safety razor comprising a frame having a handle and a base extending on one side of the handle, means on the frame to movably support a blade, said extending portion of the frame having lugs, and a guard having lugs pivotally attached to the first named lugs, said guard having means to retain the blade.

6. A safety razor comprising a frame having a handle and a base extending on one side of the handle, means on the frame to movably support a blade, said extending portion of the frame having lugs, and a guard having lugs pivotally attached to the first named lugs, said guard having means to retain the blade, said guard being provided with a projection extending beyond said lugs on the side opposite said retaining means.

7. A safety razor comprising a frame having a handle and a base extending on one side of the handle, means on the frame to movably support a blade, said extending portion of the frame having lugs, and a guard having lugs pivotally attached to the first named lugs, said guard having means to retain the blade, said guard being provided with a projection extending beyond said lugs on the side opposite said retaining means, said projection being provided with an opening receiving said handle.

8. A safety razor comprising a frame having a handle and a base extending on one side of the handle, means on the frame to movably support a blade, said extending portion of the frame having lugs, and a guard having lugs pivotally attached to the first named lugs, said guard having means to retain the blade, said guard being provided with a projection extending beyond said lugs on the side opposite said retaining means, said projection opposing said base to be stopped thereby when the projection moves the guard away from the blade.

Signed at New York city, in the county of New York, and State of New York, this 17th day of August, A. D. 1921.

HENRY J. GAISMAN.
